ELECTRICAL PLUG CONNECTOR

Harry Charmoy, Long Island City, N. Y., assignor
to Hatfield Wire & Cable Co., Hillside, N. J., a
corporation of New Jersey

Application March 18, 1938, Serial No. 196,632

21 Claims. (Cl. 173—361)

The present invention relates to electrical plug connectors, and as far as certain features are concerned, to connectors of the prong type, in which the root sections of a pair of spaced terminal pieces are retained in corresponding pre-formed longitudinal recesses of a one-piece pre-molded resilient plug body.

Also, as far as certain features are concerned, the invention is adapted for that type of electrical plug connector, which is assembled by drawing the terminal pieces with the conductor wires electrically attached thereto, through the respective recesses of the plug body from the neck end of said body, until the prong sections of said pieces extend outwardly beyond the face end of said body, and the roots of said pieces are embedded in said recesses.

One object of the invention is to provide an electrical plug connector of the type referred to, in which terminal pieces are accurately positioned longitudinal and firmly retained in the recesses of the resilient plug body, without the use of screws, rivets or other similar fastening means.

Another object is to provide a male plug connector having terminal pieces with spring prongs, which retain their resiliency under the most severe conditions of use, which, when inserted in a socket plug, will be firmly retained in electrical contact therewith, and which can be withdrawn therefrom without catching in said socket plug.

Another object is to provide terminal pieces, having spring prong fingers affording the greatest amount of resiliency, while presenting the maximum amount of contact area, so that said fingers will yield readily into effective electrical contact with the terminals of a socket plug, with a minimum amount of distortion of said terminals.

In carrying out the invention, each terminal piece is made from a single flat strip of metal, reversely bent at opposite ends to form a spring contact finger at the prong section, and to afford at the root section the double thickness required to completely fill the corresponding recess in the plug body, after said prong section with its double thickness has passed through said recess during assembly process.

As another feature, the terminal piece in certain embodiments of the invention, has a reversely bent prong section, with a spring portion, which extends longitudinally of, and transversely symmetrically with respect to said section, and which is free to flex longitudinally when inserted

in a socket plug, the unsprung portion of said section having anchoring means with respect to the resilient plug body.

As another feature, the terminal piece of certain embodiments of the invention has a reversely bent prong section, divided longitudinally to form at least two spring fingers, independently yieldable into electrical contact with the terminals of a socket plug.

10 In the accompanying drawings, in which are shown one or more of various possible embodiments of the several features of the invention,

Fig. 1 is a perspective view of one form of assembled plug connector, embodying the present invention,

Fig. 2 is a longitudinal cross-section of the assembled plug connector of Fig. 1,

Fig. 3 is a front elevation of one of the terminal pieces of the plug connector of Fig. 1,

20 Fig. 4 is a longitudinal section of the terminal piece, taken on line 4—4 of Fig. 3,

Fig. 5 is a rear elevation of the terminal piece of Figs. 3 and 4,

Fig. 6 is a side elevation, partly in section, showing the first stage in the mounting of the terminal pieces of Figs. 3 to 5 in the plug body,

Fig. 7 is a longitudinal section of a portion of the plug body, with another form of terminal piece mounted therein,

30 Fig. 8 is a perspective view of the terminal piece of Fig. 7, showing one of its spring fingers partly broken off for the sake of clearness,

Fig. 9 is a longitudinal section of a portion of the plug body, with another form of terminal piece mounted therein,

Fig. 10 is a perspective view of the terminal piece of Fig. 9, showing one of the spring fingers partly broken off,

Fig. 11 is a longitudinal section of a portion of the plug body, with another form of terminal piece mounted therein,

Fig. 12 is a perspective view of the terminal piece of Fig. 11, showing one of its prong sections partly broken off,

45 Fig. 13 is a longitudinal section of a portion of the plug body, with still another form of terminal piece mounted therein, and

Fig. 14 is a perspective view of the terminal piece of Fig. 13, and showing one of its spring fingers partly broken off.

Referring now to the drawings, there is shown in Fig. 1 an electrical connector plug, including a premolded one-piece flexible insulating body 10, desirably made of soft rubber composition, a pair of transversely spaced terminal pieces 11, firmly

embedded in said body, and having prong sections 12 protruding outwardly from the face 13 thereof for electrical engagement with the usual socket plug (not shown), and a flexible electrical conductor cord 14 protruding from the neck 15 of said body.

The plug body 10 is provided with pre-formed passageways comprising a center longitudinal recess or port 16, extending through the neck 15 thereof for housing the conductor cord 14, a pair of substantially parallel recesses 17 extending to the face 13 of said body for frictionally receiving the root sections 18 of the terminal pieces 11, and interspaced by a central plug body section 19, and a pair of recesses 20 diverging from said center recess 16, and communicating with the inner ends of said recesses 17 respectively. The body section 19 has a pair of inclined surfaces 21 at its inner ends, serving to form seats for offset portions of the terminal pieces 11 as will be more fully described hereinafter, and the diverging recesses 20 are provided with bays 22 on their outer sides for receiving the enlargements formed by the terminal connections between the bare ends 23 of the conductor cord 14 and the inner terminal ends of said pieces.

In the form shown in Figs. 1-6, each of the terminal pieces 11 is made from a single flat strip of resilient metal such as brass, and includes a main backing section 24, reversely bent sharply at 26 to form a prong spring finger 25, and a section 27 at its other end reversely bent sharply at 28 in close overlapping relationship with said backing section, and forming therewith the root 18 of double thickness adapted to be embedded in the corresponding recess 17 of the plug body 10. The spring finger 25 has its free end spaced from the backing section 24, and is desirably slightly bowed outwardly lengthwise thereof, so that said free end will not catch in the contact socket of a socket plug (not shown) when said spring finger is being pulled out therefrom.

The backing section 24 and the spring finger 25 are desirably provided with registering holes 29 near the fold line 26, for receiving a pair of hook members 41 in the operation of mounting the terminal piece in the plug body as shown in Fig. 6, and as will be hereinafter more fully described.

The terminal strip is sharply crimped at the bent section 28 to form an oblique offset 30, which is adapted to seat on the corresponding inclined surface 21 of the plug body 10, and which is desirably provided with a notch 31 in the center thereof for receiving the bare end 23 of one corresponding conductor wire in the formation of the electrical connection between said wire and the terminal piece 11. This notch 31 is desirably formed by punching a hole through the terminal strip prior to the bending and crimping thereof, and reversely bending said strip across the center of said hole along the fold line 28. This hole serves not only to form the notch 31, but also serves to weaken the strip along the fold line 28 so that it may be easily bent along said line.

In the formation of the electrical connection between a wire and the terminal piece 11, the bare end 23 of said wire also passes desirably through registering holes 32 formed in the backing section 24 and the overlapping section 27 of said terminal piece.

The bent-over section 27 has a substantially triangular tongue 33 struck therefrom to form a barb directed toward the root end of the terminal piece and serving to engage the plug body 10, so

as to accurately locate the terminal piece 11 longitudinally of said plug body as will be more fully described hereinafter.

The free ends 34 and 35 of the bent terminal sections 25 and 27 respectively are a comparatively short distance apart and the backing section 24 is provided with an embossing 36 extending longitudinally across the space between said ends to impart substantial rigidity to said backing section where the terminal piece is of single thickness.

In the operation of mounting the terminal pieces into the plug body, the end of the conductor cord 14 is split to form a pair of branch conductors 40, and the outer bare ends 23 thereof are passed through the notches 31 and through the registering openings 32 of the terminal pieces 11, and desirably soldered therein to form strong electrical connections therewith. The two terminal pieces 11 as shown in Fig. 6 with the wires electrically connected thereto and the spring fingers 25 facing each other, are positioned on the neck side of the clamped plug body 10 preliminary to the assembly operation. A pair of spaced fingers 41 having hooks 42 at their outer ends are then forced respectively through the recesses 17, 20 and then through the center recess 16 of the plug body 10 from the face end 13 thereof, until said hooks extend outwardly beyond the neck of said plug body.

In the molding of plug body 10, thin walls 43 are formed between the mold cores dividing the recesses 20 and the center recess 16. These thin walls 43 are ruptured when the hooked fingers 41 are forced therethrough, and for the purpose of clearness are shown in Fig. 6, but not in Fig. 2. After the hook fingers 41 are passed through the plug body 10 as shown in Fig. 6 the hook ends 42 thereof are slipped through the registering openings 29 of the terminal pieces 11. These hook fingers 41 are then retracted through the plug body, carrying with them the terminal pieces 11, these fingers 41 being given the necessary lateral movement corresponding to the sinuous shapes of the various recesses of the plug body as they pass therethrough, until the root sections 18 of said terminal pieces are properly positioned in the recesses 17 respectively with their offset sections 30 seated upon the inclined surfaces 21 of said plug body. In this mounted position of the terminal pieces 11, the backing sections 24 of the respective terminal pieces 11 will be parallel to each other, the spring fingers 25 will face each other, and the free ends of said fingers will extend a small distance beyond the face end 13 of the plug body 10, so that said fingers will not bind on said face end, and will be free to flex when inserted in a socket plug (not shown). The tongues 33 by their engagement with the plug body 10 serve to prevent the retraction of the terminal pieces into the interior of said body 10, thereby assuring against the binding of the spring fingers on the face end 13 of said body. When the terminal pieces 11 are brought home in their proper position indicated, the hook fingers 41 are disengaged from the terminal piece 11.

The cross-section of each recess 17 of the plug body 10 is such that the root section 18 of the corresponding terminal piece 11 will be frictionally gripped firmly therein by the resilient material of the plug body. Since this recess 17 must be large enough to permit the passage therethrough of the double thickness of the prong section 12 of the terminal piece during

the assembling operation, which double thickness is no greater than that of the root section 18, the double thickness at said root section will assure the complete filling of said recess so that said terminal piece will be held firmly in position. The double thickness at this root section serves not only to completely fill the recess 17, but also serves to impart substantial rigidity to the offset 30, which by its seating engagement with the body seat 21 will effectively resist the most severe pulling stress on the terminal piece encountered during use. The embossing 36 on the backing section 24, extending from opposite sides of the body face 13, serves to strengthen said backing section against transverse bending, especially at said body face where said bending would otherwise be apt to take place.

As far as certain aspects of the invention are concerned the prong section 12 of the terminal piece 11 may be made without the spring finger 25, so that said section will be of a single thickness. In that case the recess 17 will permit the easy passage of this prong section therethrough during the assembling operation, but will be completely filled by the double thickness of the root section in assembled position.

In the forms shown in Figs. 7 to 14, there is provided a reversely bent prong section, with a spring portion, which extends longitudinally of and transversely symmetrically with respect to said section, and which is free to flex longitudinally, when inserted in a socket plug, the unsprung portion of said section having anchoring means with respect to the resilient plug body.

In common with the terminal piece shown in Figs. 1 to 6, the terminal piece shown in Figs. 7 and 8 is made from a single flat strip of resilient metal, and has a main backing section 24a, and a reversely bent section 21a at one end, forming with said backing section a root 18a, provided with an end oblique offset 30a for seating engagement in the plug body, and openings 31a and 32a for receiving the bare ends of a conductor wire.

The modified form of prong includes a section 50, reversely bent sharply from the outer end of the main backing section 24a, and having an outer end portion 51, of substantially length in contact with said backing section, to facilitate entry of the prong into a socket plug. The inner end portion of the prong section 50 is divided longitudinally to its unattached end desirably by a pair of parallel slits 54, to form a central straight flat member 55, and a pair of side members 56 of equal length. These side members 56 are bent obliquely outward from the backing section 24a to form substantially straight relatively yieldable spring contact fingers, and the central prong member 55 is in contact with the backing section 24a, and desirably formed at its unattached end with an oblique barb 58, beyond the free ends of the spring fingers 56.

The two prong sections 24a and 51 are provided with registering holes 29a for engagement by the pulling hooks 42 shown in Fig. 6, during the assembling operation.

In the plug assembled position shown in Fig. 7, the root 18a of the terminal piece is retained in the corresponding recess 17 of the plug body 10 as already described with reference to the construction of Figs. 1 to 6, the free ends of the spring fingers 56 extend a small distance beyond the face end 13 of the plug body to permit ready transverse flexure of said fingers, and the inner end of the central prong member 55 is anchored

in said recess, with the barb 58 biting into the plug body section 19 to prevent the retraction of the terminal piece into the interior of the plug body. This central prong member 55 also serves to bring the contact area of the terminal piece to that required by the Board of Underwriters, and to form with the backing section 24a, a double thickness at the face end 13 of the plug body, affording the necessary strength against transverse bending without the necessity of embossing said backing section.

Since the two spring fingers 56 are relatively yieldable transversely, the prong will more readily yield into effective electrical contact with the corresponding terminal member of a socket plug, so that permanent distortion of said terminal member by said contact is obviated.

In the form of plug connector shown in Figs. 9 and 10, the root 18b of the terminal piece is exactly like that shown in Fig. 8, and the prong is formed by reversely bending a section 60 at one end of the backing section 24b into contact with said backing section. This prong section 60 is longitudinally divided to its unattached end, desirably by parallel slits 62, to form a straight central member 63 in contact with the backing section 24b, and a pair of similar members 64. The central member 63 terminates at its inner unattached end in an oblique barb 65, corresponding to that shown in Fig. 8, and the two side members 64 are longitudinally bowed outwardly along the main lengths thereof to form relatively yieldable spring fingers, with inner unattached ends 66 extending substantially parallel to and in contact with the backing section 24b.

In the plug assembled position shown in Fig. 9, the root 18b of the terminal piece is held in its respective plug recess 17, the prong extends beyond the face end 13 of the plug body 10, and the offset end 65 of the central prong member 63, as well as the ends 66 of the spring fingers 64 are retained in said recess. By means of this construction, the spring fingers 64, with their inner ends 66 held against transverse movement, but free to slide longitudinally in the recess 17, will flex longitudinally into electrical engagement with the contact blade of a socket plug, by a snap action when inserted therein, and the possibility of these spring ends 66 catching in the plug socket, when the terminal piece is being pulled out therefrom is obviated. Furthermore, there is no possibility that these fingers will lose their resiliency, or that they will be bent permanently into ineffective position close to the backing section 24b after a period of use.

In the form shown in Figs. 11 and 12, the terminal piece has a root 18c, identical with that shown in the construction of Figs. 7 and 8, and the prong is formed with a reversely bent section 70, longitudinally divided to its unattached inner end, desirably by a pair of parallel slits 71, to form a pair of similar straight side members 72, and a central member 73. This central member 73 is bowed outwardly to form a spring finger, and terminates at its inner end in a section 74, parallel to and in contact with the backing section 24c. The inner unattached ends of the side members 72 terminate in offset barbs 75.

In the assembled position shown in Fig. 11, the root 18c of the terminal piece is retained in its respective plug recess 17, and the end 74 of the spring finger 73, as well as the offset ends 75 of the side members 72, are anchored in said

recess against lateral movement with respect to the backing section 24c so that the terminal piece is held against retraction in the plug body, and the spring finger 73, has a snap action when inserted in a plug socket, and will not catch in said socket when withdrawn therefrom. This spring finger 73 is free to flex longitudinally, since the unattached end 74 thereof can slide longitudinally in the recess 17.

The construction of Figs. 13 and 14 is similar to that shown in Figs. 7 and 8, except that the spring fingers 80, instead of extending obliquely straight along their entire lengths from the reversely bent prong section 81, have respective portions 82 extending obliquely with respect to the backing section 24d, and respective portions 83 extending substantially parallel thereto. This construction may be desirable for use with certain types of socket plugs, since the spring fingers 80 will be substantially parallel to the plug socket when inserted therein, thereby assuring greater contact area with the contact blades of said socket.

All of the constructions shown in Figs. 7 to 14 are desirably assembled in a manner indicated with reference to the construction of Figs. 1 to 6, and as far as certain aspects of the invention embodied in these constructions of Figs. 7 to 14 are concerned, the roots of the terminal pieces may be made of a single thickness.

As many changes could be made in the above article and many apparently widely different embodiments of this invention could be made without departing from the scope of the claims, it is intended that all matter contained in the above description or shown in the accompanying drawings shall be interpreted as illustrative and not in a limiting sense.

Having thus described my invention what I claim as new and desire to secure by Letters Patent is:

1. As an article of manufacture, an electrical terminal piece, adapted to be embedded in the pre-formed recess of a one-piece pre-molded resilient plug body, and comprising a strip-like member having a main backing section, a section at one end thereof reversely bent to provide with said backing section a double ply root having a bent double ply end for anchoring engagement in such recess, and a section at the other end of said backing section reversely bent to form a spring finger extending along the length of said backing section, said spring finger and the opposed portion of said backing section being adapted to extend beyond the face end of such plug body to form a contact prong, the free ends of said reversely bent sections extending to near the corresponding portion of said backing section and being spaced apart.

2. As an article of manufacture, an electrical terminal piece, adapted to be embedded in the pre-formed recess of a one-piece pre-molded resilient plug body, and comprising a strip-like member having a main backing section, a section at one end thereof reversely bent to provide with said backing section a root of double thickness for frictional engagement in said recess, and a section at the other end of such backing section reversely bent to form a spring finger, said spring finger and the opposed portion of said backing section being adapted to extend beyond the face end of such plug body to form a contact prong, the free ends of said reversely bent sections being spaced apart, and the portion of said backing section between the free ends of

said reversely bent sections being provided with a longitudinal embossing to strengthen the portion of said terminal piece of single thickness against transverse bending.

3. As an article of manufacture, an electrical terminal piece, adapted to be embedded in a pre-formed recess of a one-piece resilient plug body and comprising a strip-like member having a main backing section, a section at one end thereof reversely bent with respect thereto and forming therewith a root of double thickness for frictional engagement in such recess, a section at the other end reversely bent with respect thereto and forming a spring finger, the free ends of said reversely bent sections being spaced apart, the portion of said backing section between said free ends being provided with an embossing extending lengthwise of said backing section for imparting rigidity to said backing section, and said root having a tongue struck from one of the overlapping layers thereof, adapted to engage such plug body to prevent retraction of said terminal piece into such plug body in assembled position.

4. An electrical plug connector of the prong type, including a one-piece resilient plug body having a central recess extending through the neck end thereof, and a pair of spaced parallel recesses communicating with said central recess, a pair of terminal pieces each having a main backing section, a section at one end thereof transversely bent to provide with said backing section a root of double thickness frictionally retained in one of said spaced recesses, and a section at the other end of said backing section reversely bent to form a spring finger, each of said spring fingers and the opposed portion of the corresponding backing section extending outwardly beyond the face end of said plug body to form a contact prong, the free ends of said reversely bent sections being spaced apart, and the portion of said backing section between said free ends being provided with a longitudinally extending embossing to strengthen said backing section against transverse bending, and a conductor cord extending through said central recess and presenting bare wires at its ends, electrically connected to the inner ends of the respective terminal pieces.

5. An electrical plug connector of the prong type, including a one piece resilient plug body, having a central recess through the neck end thereof, a pair of substantially parallel spaced elongated passageways extending to the face end of said plug body, and a pair of spaced recesses diverging from said central recess and communicating with the respective inner ends of said parallel passageways, said passageways defining therebetween a plug body section affording a pair of spaced inclined surfaces at its inner end adjacent to the respective inner ends of said passageways, a pair of terminal pieces having doubled over root sections at their inner ends frictionally retained in the respective passageways, and having double ply inturned offsets at said inner ends seated upon said inclined surfaces, and prongs at their outer ends extending outwardly beyond the face end of said plug body, and a conductor cord extending through said central recess, and having a pair of diverging branches in the respective diverging recesses, presenting bare wires at their ends, electrically connected to the inner ends of the respective terminal pieces.

6. An electrical plug connector of the prong

type, including a one piece resilient plug body having a central recess through the neck end thereof, a pair of substantially parallel spaced elongated passageways extending to the face end of said plug body, and a pair of spaced recesses diverging from said central recess, and communicating with the respective inner ends of said passageways, said recesses having laterally outwardly extending bays on the respective outer sides thereof, a pair of terminal pieces having doubled root sections at their inner ends with the inner extremities thereof turned inward to form double ply offsets anchored in said diverging recesses, the lengths of said root section being frictionally retained in their respective parallel passageways, and prongs at their outer ends extending outwardly beyond the face end of said plug body, and a conductor cord extending through said central recesses, and having branch sections in said diverging recesses, presenting bare wires at their respective ends, with electrical connections to the inner ends of the respective terminal pieces, the enlargements formed by said electrical connections extending in the respective bays of said diverging recesses.

7. An electrical plug connector of the prong type, including a one piece resilient plug body, having a central recess through the neck end thereof, a pair of substantially parallel spaced elongated passageways communicating with said central recess, and a pair of recesses diverging from said central recess and toward the respective inner ends of said passageways, thin webs extending across the respective recesses, a pair of terminal pieces having root sections frictionally retained in the respective passageways and prongs at the outer ends thereof extending outwardly beyond the face end of said plug body, a conductor cord extending through said central recess and having branch connections passing through said diverging recesses, extending through and engaged by said webs, and electrically connected at the inner ends thereof to the respective terminal pieces.

8. As an article of manufacture, a terminal piece, adapted to be retained in a resilient plug body, and comprising a strip-like member, having a main backing section, and a prong section at one end, reversely bent, and slit longitudinally to form a pair of relatively yieldable spring fingers said fingers being bowed for resiliency.

9. As an article of manufacture, a terminal piece, adapted to be retained in a resilient plug body, and comprising a strip-like member having a main backing section, and a prong section at one end, reversely bent, having parallel slits extending longitudinally to the unattached end of the prong section, the metal between a pair of said slits being bowed outwardly solely at the median part of its length.

10. As an article of manufacture, a terminal piece, adapted to be retained in a resilient plug body, and comprising a strip-like member, having a main backing section, and a prong section at one end reversely bent, and divided longitudinally to its unattached end to form a pair of adjoining members, one of said members being in close lapping proximity to said backing section throughout substantially the entire length of said member, and having its inner unattached end adapted to be retained in said plug body in assembled position, the other member being bent outwardly to form a spring finger.

11. As an article of manufacture, a terminal

piece adapted to be retained in a resilient plug body, and comprising a strip-like member, having a main backing section, and a prong section at one end reversely bent and divided longitudinally to its unattached end to form a pair of adjoining members, one of said members having an outwardly bent portion to form a spring finger, and one of said members having at its inner unattached end an offset, adapted to be retained in said plug body in assembled position, and to prevent the retraction of said terminal piece into the interior of said plug body.

12. As an article of manufacture, a terminal piece, adapted to be retained in a resilient plug body, and comprising a strip-like member, having a main backing section, and a prong section at one end reversely bent and divided longitudinally to its unattached end to form a pair of adjoining members, one of said members, having an outwardly bent portion to form a spring finger, the other member being substantially flat and in contact with said backing section, and having at its outer unattached end an offset, adapted to be retained in said plug body in assembled position, and to prevent the retraction of said terminal piece into the interior of said plug body.

13. As an article of manufacture, a terminal piece, adapted to be retained in a resilient plug body, and comprising a strip-like member, having a main backing section, and a prong section at one end reversely bent, and divided longitudinally to its unattached end to form three adjoining members, the two outer members being bent outwardly to form spring fingers, and the middle member lying in close lapping proximity to said backing section substantially throughout the entire length of said middle member, and having its inner unattached end adapted to be retained in said plug body in assembled position.

14. As an article of manufacture, a terminal piece, adapted to be retained in a resilient plug body, and comprising a strip-like member having a main backing section, and a prong section at one end reversely bent, and divided longitudinally to its unattached end to form three adjoining members, the two outer members being bent outwardly to form spring fingers, the middle member being substantially flat and in contact with said backing section, and having at its inner unattached end an offset, adapted to be retained in said plug body in assembled position, and to prevent the retraction of said terminal piece into the interior of said plug body.

15. As an article of manufacture, a terminal piece, adapted to be retained in a resilient plug body, and comprising a strip-like member having a main backing section, and a prong section at one end reversely bent, and divided longitudinally to its unattached end to form two adjoining members, one of which is bent outwardly to form a spring finger adapted to have its free end spaced from the face end of the plug body in assembled position, the unattached end of the other member extending beyond the free end of said spring finger towards the other root end of the backing section, and being adapted to be retained in said plug body in assembled position.

16. As an article of manufacture, a terminal piece, adapted to be retained in a resilient plug body, and comprising a strip-like member having a main backing section, and a prong section at one end reversely bent and divided longitudinally to its unattached end to form two adjoining members, the opposed prong sections of said

terminal piece at their socket entry end being crimped into contact with each other, one of said members being bent obliquely outwardly along a straight line to the free end thereof to form a spring finger, the free end of said spring finger being adapted to be spaced from the face end of said plug body to permit transverse spring movement thereof, the other member being flat throughout substantially its entire length and in contact with said backing section, the unattached end of said latter member being adapted to be retained in the plug body in assembled position.

17. An electrical plug connector of the prong type, including a one piece resilient plug body, having a central opening extending to the neck end of said plug body, and a pair of spaced recesses communicating with said central opening, and a pair of terminal pieces each having a backing section frictionally retained in its corresponding recess, and having a reversely bent section forming with said backing section a prong, said bent section being divided longitudinally to form a pair of relatively yieldable spring contact fingers.

18. An electrical plug connector of the prong type including a one piece resilient plug body, having a central opening extending to the neck end of said plug body, and a pair of spaced recesses communicating with said central opening, and a pair of terminal pieces, each having a backing section, frictionally retained in its corresponding recess, and having a reversely bent section forming with said backing section a prong, said bent section being divided longitudinally to its unattached end to form a pair of adjoining members, one of said members being bent outwardly to form a spring finger, the other member having its inner end anchored in its respective recess.

19. An electrical plug connector of the prong type, including a one piece resilient plug body,

having a central opening extending to the neck end of said plug body, and a pair of spaced recesses communicating with said central opening, and a pair of terminal pieces, each having a backing section, frictionally retained in its corresponding recess, and having a reversely bent section, forming with said backing section a prong, said bent section being divided longitudinally to its unattached end to form a pair of adjoining members, one of said members being bent outwardly to form a spring finger, the other member having an inner offset end anchored in its respective recess, and engaging the wall of said recess to prevent retraction of said terminal piece into the interior of the plug body.

20. As an article of manufacture, a terminal piece, adapted to be retained in a resilient plug body, and comprising a strip-like member, having a main backing section, and a prong section at one end, reversely bent, and divided longitudinally to its unattached end to form a pair of members, bowed outwardly to form relatively yieldable spring fingers, the inner unattached ends thereof extending parallel to and in contact with said backing section.

5 21. As an article of manufacture, a terminal
piece, adapted to be retained in a resilient plug
body, and comprising a strip-like member, hav-
ing a main backing section, and a prong section
0 at one end, reversely bent, and divided longi-
tudinally to its unattached end to form three
adjoining members, the central member being
in close overlapping relationship with said back-
ing section, and having an offset at its inner end
5 for anchorage in said plug body, the other side
members being bowed outwardly to form rela-
tively yieldable spring fingers, the inner unat-
tached ends thereof extending parallel to and in
close overlapping relationship with said backing
0 section, and being adapted to be retained in said
plug body.

HARRY CHARMOY.
